UNITED STATES PATENT OFFICE.

CHARLES A. WALOUKE, OF CLEVELAND, OHIO.

AIR DISTRIBUTOR.

Application filed May 3, 1926. Serial No. 106,270.

This invention relates to air distributers, and especially to such devices as applied to furnaces in which a central fire pot is provided for combustion, the smoke and other products of the combustion passing off at the upper part of the furnace, and the fuel being ordinarily directed as a gas into the lower portion of the fire chamber or deposited as solids just above the ash grate.

10 My invention relates especially to fuel economizers whereby many of the products ordinarily passing off through the chimney may be used in a more perfect combustion resulting in a great saving of fuel. It is well known that much of the fuel waste in furnaces is due to the fact that not sufficient oxygen is supplied at the point where combustion is supposed to take place, or that the outside air entering the fire chamber through the usual 15 draft openings is supplied at so low a temperature that the combustion is imperfect and incomplete. My improved distributor is designed to overcome both of these defects, supplying an adequate amount of oxygen by an air current in a heated condition and directed to the proper point for perfect combustion.

It is an object of my invention to arrange a device having hollow tubular construction mounted upon the walls of the furnace and 20 penetrating the same so that the air directed through it will be forced out at a point somewhat above the flames in the fire chamber, usually at a point substantially the level of the upper portion of the furnace door. In 25 my improved construction, I insert the tube leading to the device through the furnace wall at the rear of the furnace opposite the door or at either side, though in some cases it may be desirable to introduce the distributor 30 pipe just above or at one side of the door.

40 It is a further object of my invention to so attach the distributor pipe to the wall opening through which it is directed, that the connections at the wall will serve as a means of mounting the distributor within the chamber.

45 With these and other objects in view, I have invented a construction embodying the features herein described and illustrated in the accompanying drawings, in which—

Figure 1 is a vertical section of a hot air furnace showing my improved air distributor in operative position within the fire chamber;

50 Figure 2 is a plan view of the air distributor in position, a portion of the upper covering

plate being removed, and the furnace wall shown in section;

Figure 3 is a plan view of a modified form of the device, shown in a larger scale and omitting the attachment with the furnace wall;

Figure 4 is a vertical section of the device shown in Fig. 3, taken on the line 4—4 of Fig. 3;

Figure 5 is a cross section taken on the line 5—5 of Fig. 3;

Figure 6 is a cross section taken on line 6—6 of Fig. 3;

Figure 7 is a view, partly in section showing a form of the device mounted upon the rear 70 wall of a water heating furnace with the walls of the furnace in section.

In Fig. 1, I have shown my improved air distributor 1 as an annulus 2 formed of hollow pipe structure, here shown as rectangular 75 in cross section but not necessarily so, and having a number of apertures 3 in the walls of this pipe. When the cross section is rectangular, the apertures in the upper and lower plate of this pipe will preferably be arranged 80 in staggered relation, as shown in Fig. 2, while the apertures in the side walls will also be staggered, and not directly opposite the top and bottom apertures, when this can be done. This ring 2 is supported by an integral 85 pipe 4 connected by an intermediate pipe 5 which leads from the outer wall of the furnace to the wall of the fire chamber 6. The parts 4 and 5 will be connected together by suitable flanges 7 and fixedly secured to the 90 chamber wall by bolts 8, the parts usually being rendered gas proof by suitable packing such as asbestos, fibre or other suitable means for avoiding leakage. It has been found highly advantageous to telescope in some way, the 95 connecting ends of the sections 4 and 5, as by inserting the reduced end 9 of the tube 5 within the opening 10 of the pipe 4. This construction has been found highly effective in making the joint leak-proof. The bolts 100 8 are inserted in registering apertures in the flanges of both parts 4 and 5, as well as through the walls of the chamber, so that the pipes 4 and 5 are bolted together securely and also the annulus 2 positively supported in 105 position over the center of the fire area.

The section 5, as shown in Figs. 1 and 2, conducts air from the opening 11 at the outer surface of the furnace 12, through the space between the outer furnace wall and the wall 110

of the fire chamber 6, thereby being pre-heated somewhat by the hot-air chamber 13. This is desirable, since this arrangement provides an introductory heating prior to entering the high-temperature section 4 where it is pre-heated by the fire chamber heat directly by the flames and gases therein. The opening 11 may be partially closed by a valve construction 14, here shown as swinging on a pivot 15 and held in adjusted position by the ratchet 16. It may be desirable to close this valve partially when a smaller inflow of outside air is best, as when first starting the fire.

The inner wall 17 of the annulus 2 is shaped in a wedge form at 18 so that the incoming air divides at this point and circulates about the tubular portions of the annulus 2 until it passes out into the fire chamber through the various apertures 3, as above explained. The outer end of the tubular section 5 is attached to the outer wall of the furnace by other flanges 7, and by an outer ring 19 applied to the edge of the opening in the furnace wall, the ring and flanges being bolted together in the manner that the sections are secured to the fire chamber.

In the form shown in Figs. 3 to 6, the annulus 20 is provided with the same character of apertures 3, but the lower plate 21 thereof is spaced from the upper plate a greater distance at the point of union with the section 22 which latter is modified to register with such union, this section being tubular and inclined, in the same manner as the pipe 4, with its lower end attached to the section 5, just as in the form shown in Figs. 1 and 2. In further spacing this lower plate 21, it is curved downwardly at 23 to approximately double the vertical space between the plates that they have in the balance of the annulus, and this space is divided horizontally by a web 24 having an entrance projection 25 extending into the section 22. Apertures 3 are provided in the walls of the upper chamber 26 of the enlarged tubing as in the arrangement in the annulus shown in Figs. 1 and 2. The entire vertical wall 27 at this point is formed in wedge-shape as in the first form. The section 22 may be enlarged at the upper end only, being reduced to the usual circular shape at its lower end where it connects with section 5.

In all these forms shown in Figs. 1 to 6, the annulus is shown as rectangular in cross section, and divided into double chamber form in Figs. 3 to 6 for a portion of its extent. It is to be understood that such tubing may, if desired, have some other form in cross section, such as circular or oval. The apertures 3 would be placed at different positions on the outer wall of such tube, to distribute the air at different points and in different directions therefrom, for greater effectiveness.

In Fig. 7, I have shown my air distributor as it may be applied in a water heating furnace, for it is to be understood that I am not to be limited to use thereof in an air-heating furnace only. In a water heater, the rear wall is usually a one-piece plate, designated in this view as 28. In such application of my improvement, the otherwise separate parts 4 and 5, will now be made integral as the part 29 whose upper end is integral with the annulus 2, and the lower end inserted in an opening of the plate 28 and secured therein by the flange-ring construction in much the same manner as the part 5 is attached to the furnace wall, in Figs. 1 and 2. In this construction, as in those shown in Figs. 1 to 6, inclusive, the annulus is supported solely by the inclined pipe from the furnace wall, and in a position centrally over the fire area, so that the only partially burned gases from the fuel will receive oxygen supply from the distributor and again burn in a heating flame of great intensity.

The purpose of all these constructions is to make feasible a preheating of the air introduced into the fire chamber, and do this by a construction admitting of ready assembly when mounted within a new furnace, but especially admitting of application to furnaces already assembled and mounted in a building, and possibly already in use for some time. This makes quite essential that the pre-heating tube—4 or 22, shall not be attached to any part of the furnace other than at the opening therein where the tubes are inserted.

Operation.—My improved structure is adapted for mounting within the fire chamber of all types of furnaces. I have illustrated it as mounted on either air current furnaces or water heating furnaces. It is obvious that it is adapted equally well for use in steam or vapor furnaces, it being only essential that tubing being provided that shall pierce the walls between the external surface of the furnace and the fire chamber.

It is to be noted that when the inner wall of the fire chamber is spaced appreciably from the outer furnace wall, as in Fig. 1, the intermediate section, shown here as 5, must be mounted between and upon these walls, and that the connection made by this section with the outer surface and with the support section, must be one that is leak-proof. When my improvement is to be mounted upon an air current furnace, therefore, the walls 6 and 12 are bored, the section 5 mounted between these walls, and the distributor device mounted within the chamber 6 by inserting the end 10 of the section 4 within the aperture of the wall 6 telescoping the end of section 5, and the flanges 7 then bolted securely together and to the chamber wall 12. This mounts the apertured annulus of the form shown in Figs. 1 to 7, directly

above the center of the fire area of the fire chamber. As the air in the section 5 is heated as it passes therethrough outside the fire chamber, it enters the latter already 5 moderately heated, when it is further and more positively pre-heated by the high temperature of the gases in the said chamber. The air supply from said distributer will therefore be discharged from the various 10 apertures 3 of the device highly heated and very well adapted to support combustion of any gases arising from the fire area below and thereby resulting in a far more perfect combustion thereof. This of course, reduces 15 the quantity of smoke emitted from the smoke flue—a very valuable function of my improved device. In fact, the use of my air distributer in the fire chambers of furnaces will almost eliminate smoke bearing un- 20 burned matter from such furnaces.

In all forms I have shown in these drawings, a prominent feature is the apertured and extended tubular member which distributes the oxygen-bearing outside air just 25 where it is needed for complete combustion of the fuel elements, and which member is readily mounted upon the furnace walls. This feature is, to my knowledge, new and 30 patentable.

Having described my invention, what I claim and desire to secure by Letters Patent, is—

1. The combination with a furnace having a fire chamber spaced interiorly thereof, of 35 an air distributer comprising an annular tubing polygonal in cross section and having apertured walls and a horizontal partition plate within said tubing and dividing the air space at the entrance portion of the tubing 40 into an apertured upper space and an imperforate lower space, an imperforate tubular section connected integrally with said tubing and inclined downwardly from said tubing within the fire chamber and mounted 45 upon the wall of the chamber by attachment 50 concentric with an aperture of said wall, a horizontal tubular section connecting the aperture in the chamber wall with an aperture in the outer wall of the furnace, so that 55 outer air may pass through the horizontal and inclined sections to the annular tubing and above and below the said partition plate and thence escape through said tube apertures, the said tubing with apertured walls being supported solely by the said inclined section.

2. The combination with a furnace having a fire chamber spaced interiorly thereof, of 60 an air distributer, comprising a curved tubu- 65 lar portion positioned over the fire area of the fire chamber of said furnace, an inclined

and imperforate portion leading downward and outward from said curved portion mounted upon the walls of said furnace, a tubular section connecting the walls of the 65 furnace and of the chamber by having its ends piercing the said walls, respectively, the inner end of said section telescoping the lower end of said inclined section, and means on the outer surface of the furnace wall for adjustably closing the outer end of said tubular 70 section.

3. The combination with a furnace having a fire chamber spaced interiorly thereof, of 75 an air distributer comprising an annular tubing polygonal in cross section and having apertured walls, an imperforate tubular section connected with said apertured tube at one end and inclined downwardly from said tubing within the fire chamber and mounted 80 upon the wall of the chamber by attachment concentric with an aperture of said wall, and a horizontal tubular section connecting the aperture in the chamber wall with an aperture in the outer wall of the furnace, so that 85 outer air may pass through the horizontal and inclined sections to the annular tubing and thence escape through said tube apertures, the said tubing with apertured walls being supported solely by the said inclined 90 section.

4. The combination with a furnace having a fire chamber spaced interiorly thereof, of 95 an air distributer comprising an annular tubing polygonal in cross section and having apertured walls and a horizontal partition plate within said tubing and dividing the air space at the entrance portion of the tubing 100 into an apertured upper space and an imperforate lower space, an imperforate tubular section connected with said tubing and inclined downwardly from said tubing within the fire chamber and mounted upon the wall of the chamber by attachment concentric with an aperture of said wall, a horizontal tubular section connecting the aperture in the chamber wall with an aperture in the outer wall of the furnace, so that outer 105 air may pass through the horizontal and inclined sections to the annular tubing and there divide at the said partition plate, the air above the plate thence escaping through said tube apertures and the air below the plate passing to a point beyond the plate and thence escaping through the farther tube apertures, the said tubing with apertured walls being supported solely by the 110 said inclined section.

In witness whereof I have hereunto set my hand this 28th day of April, 1926.

CHARLES A. WALOUKE.
